United States Patent Office

Des. 192,203

Patented Feb. 6, 1962

192,203

NARROW WOVEN FABRIC OR SIMILAR ARTICLE

Inge Petsche, Old Greenwich, Conn., assignor to The Barmen Lace Corporation, Stamford, Conn., a corporation of New York

Filed Sept. 19, 1961, Ser. No. 66,754

Term of patent 7 years

(Cl. D92—1)

Fig. 1.

Fig. 2.

FIG. 1 is a plan view of a narrow woven fabric or similar article, embodying my new design.

FIG. 2 is a side elevational view thereof.

I claim:

The ornamental design for a narrow woven fabric or similar article, substantially as shown.
